UNITED STATES PATENT OFFICE.

HENRY H. KINSEY, OF SHOSHONE, IDAHO, ASSIGNOR OF ONE-THIRD TO
MALISSA TUSLER, OF ST. PAUL, MINNESOTA.

COLLAPSIBLE BOX.

SPECIFICATION forming part of Letters Patent No. 696,451, dated April 1, 1902.

Application filed June 11, 1901. Serial No. 64,102. (No model.)

To all whom it may concern:

Be it known that I, HENRY H. KINSEY, a citizen of the United States, and a resident of Shoshone, in the county of Lincoln and State 5 of Idaho, have invented a new and Improved Collapsible Box, of which the following is a full, clear, and exact description.

This invention relates to improvements in collapsible or knockdown boxes employed for shipping purposes; and the object is to provide a box of this character that may be folded and secured together in a compact manner for reshipment and that will be comparatively light, yet strong and rigid when in position for holding articles to be transported.

I will describe a collapsible box embodying my invention and then point out the novel features in the appended claims.

Reference is to be had to the accompanying 20 drawings, forming a part of this specification, in which similar characters of reference indicate corresponding parts in all the figures.

Figure 1 is a perspective view of a box embodying my invention. Fig. 2 is a section on the line *x x* of Fig. 1. Fig. 3 is a section on the line *y y* of Fig. 2. Fig. 4 is a section on the line *z z* of Fig. 2. Fig. 5 is an edge view showing the several members of the box as packed together, and Fig. 6 is a fragmentary 30 view showing a means for holding the side and end members together.

Referring to the drawings, 1 designates the bottom of the box, and 2 the end pieces thereof, having hinged connection with the bottom, as indicated at 3, so as to swing downward closely upon the bottom when the parts are folded. The ends of the end pieces are provided with metal plates 4, which are turned inward, as at 5, to provide keepers to receive 35 the ends of the side pieces 6 and to prevent any possible movement outward of the side pieces relatively to the end pieces when the parts are assembled in box position. Hooks 7, attached to the upper edges and at the 40 ends of the side pieces, engage over the metal strips 4, as plainly indicated in Fig. 6, to hold the ends securely in place. It will also be noted that the side pieces are provided at the 45 ends with metal plates 8. These several 50 metal plates materially strengthen the ends

of the pieces and prevent the breaking thereof by coming in contact with hard substances.

The removable cover 9 for the box has metal flanges 10 at its ends for engaging over the upper portion of the end pieces, and at 55 one end of the cover is a metal hook 11, designed to engage with a loop 12 on one of the end pieces, and at the opposite end of the cover is a keeper or latch designed to engage with a loop 13 on the other end piece of the box. 60 This latch or keeper consists of wire bent to form a hook portion 14, and the two members are extended inward and are mounted to swing on a pivot 15. The two inwardly-extended members are designed when the 65 hook is in engagement with the loop 13 to be engaged underneath keepers 16, formed of a single strip of wire secured to the top. It will be noted that the latch as well as the pivot-rod 15 and keeper 16 are located within an 70 opening or recess 17, formed in the top of the box, so that when the parts are in position they will be below the plane of the top of the box, and therefore will not interfere with the piling of one box evenly upon the top of another. 75

The bottom 1 of the box has flanges 18, adapted to protect the ends thereof, and on the ends are secured loops 19 20 to receive the hook 11 and the hook 14 when the parts 80 are packed together, as will be hereinafter described. To prevent any lateral movement of the side portions relatively to the top, I provide said top near its ends with downwardly-projecting staples 21, designed to engage with the sides of the side pieces. 85

The box may be divided into two or more compartments by means of partitions. I have here shown the box as divided into two compartments by means of a removable partition 90 22, consisting of two sections, one section being provided with dowels 23 to engage in openings or holes in the other section, and the bottoms of these sections are provided with dowels 24 to engage in holes formed in 95 the bottom of the box, as plainly indicated in Fig. 4. Attached to the top of the partition-sections are wire loops 25, designed to engage against the outer sides of the side pieces of the box. In lieu of nails or similar 100

devices for securing the metal strips to the members of the box V-shaped sections 26 are pressed inward from said strips and are designed to be driven into the wood of the box 5 members and clench on the under side.

In assembling the box the end sections are swung upward and then the side members or sections are slid into place, after which the partition is to be slid into place. Then to attach cover after the case has been filled the hook 11 is to be engaged with the loop 12 and the latch engaged with the loop 13. In order to engage the latch with the loop 13, the said latch at its inner end is swung upward, and 15 then as it swings downward its hook end will engage in the loop, and during this time the two inner members of the latch are to be forced toward each other so as to pass between the keepers 16, and when in the lower- 20 most position the said members are to be released so as to spring out underneath the keepers.

When the box is to be folded for reshipment, the end pieces are swung downward 25 against the bottom, one of the side pieces placed thereon, then the two sections of the partition are to be placed upon said side member, then the other side member is to be placed upon said partition-sections, and finally the 30 top is to be placed into position by first engaging the hook 11 with the loop 19 and engaging the latch with the loop 20 in a manner similar to engaging it with the loop 13.

It will be seen that a box embodying my invention may be folded in very compact form 35 and be practically smooth or level at its lower and top sides, so that several boxes may be packed closely together.

It is obvious that my invention is adapted 40 to make crates, as well as boxes, of any size, shape, or strength.

Having thus described my invention, I claim as new and desire to secure by Letters Patent—

1. A box, comprising a bottom, end pieces 45 having hinge connection therewith, loops on the upper ends of said end pieces, side pieces adapted to engage at their ends in slideways attached to the end pieces, a top, a hook at one end of said top to engage in one of the 50 loops in an end piece, and a spring-latch at the other end of said top for engaging with the loop of the other end piece the said latch being located below the plane of the cover, substantially as specified. 55

2. A box, comprising a bottom, end pieces having hinge connection therewith, metal loops on the upper ends of said end pieces, side pieces, a top, a hook on one end of said top for engaging the loop of one of the end 60 pieces, a spring-latch on the other end of said top for engaging with the loop of the other end piece the said latch being arranged below the plane of the top, and loops on the ends of the bottom for receiving said hook and 65 latch, substantially as specified.

3. A box, comprising a bottom, end pieces having hinge connection therewith, side pieces, a top or cover having loops at its side edges to engage against the outer sides of the 70 side pieces, and fastening devices for engaging the top or cover in place the said devices being below the top plane of the cover, substantially as specified.

In testimony whereof I have signed my 75 name to this specification in the presence of two subscribing witnesses.

HENRY H. KINSEY.
